GERARD SICKELS, OF BOSTON, MASSACHUSETTS.

Letters Patent No. 64,155, dated April 23, 1867.

IMPROVED SHOE-FASTENING.

The Schedule referred to in these Letters Patent and making part of the same.

TO ALL WHOM IT MAY CONCERN:

Be it known that I, GERARD SICKELS, of Boston, in the county of Suffolk, and State of Massachusetts, have invented an improved Shoe-Fastener; and I do hereby declare that the following, taken in connection with the drawings which accompany and form part of this specification, is a description of my invention sufficient to enable those skilled in the art to practise it.

This invention relates to the construction of a shoe-lacing, fastening, or tightening device, intended particularly as a substitute for shoe-buckles; and it consists in a plate or stem through or around which the lacing, strap, or other piece connecting the flaps or opposite sides of the shoe-front passes, so that by twisting or reversing, or partially reversing, this plate or stem, the slack of the lacing or strap is taken up, means being combined with the device to retain the lacing in the tightened position into which it is carried by such twisting, reversing, or turning. Many forms of the device may be used, but that which I now consider preferable is shown in the drawings at A, one part of a shoe-front being therein shown as laced or fastened, and one part as loose.

Each strap *a*, projecting from the flap *b*, passes through slots *c*, in a thin plate, *d*, the opposite end of the strap being secured to the under flap-piece *e*. Now by turning the plate *d* vertically, carrying its edge *f* down under the flap *b*, it will be readily seen that the slack in the strap is taken up by this reversal of the plate, and to hold the strap so tightened the hooked end of a slide, *g*, sliding in a fixed piece, *h*, is slipped over the edge of the plate, as shown at A. Modifications of this construction and arrangement are shown at B C D and E. At B the lacing or tie *i* passes through holes in a long plate, *k*, and the ends being secured to the opposite flap-pieces of the shoe, the plate is turned end for end, thereby twisting the lacing and taking up the slack, the plate being secured from turning back by dropping its ends between pins or projections *l*, extending up from the flap-pieces, the strain produced upon the lacing holding the plate in position, while by raising it from the projections, and allowing the lacing to untwist, the strain upon the flaps is removed, and the shoe may then be taken off. At C the string or lacing passes between two pins, joining two circular plates or disks, rotation of the plates winding the lacing around the pins and taking up the slack, the plates being kept from reverse movement by two projections at the ends of a hinge, *m*, turned down against the lacing when it is sufficiently tightened, while by turning the hinge back the lacing is allowed to unwind. At D the lacing passes between the disks and through a central stem, around which it is wound by rotation of the plates, it being kept from back movement by a locking bar, *n*. At E the lacing passes between two concave plates and through the inner one, and being wound around between them is kept in tightened position by slipping the opposite parts into notches in the edge of the upper plate.

It will be readily seen that the same invention is embodied in all of these modifications, as is shown at A, the principle being to take up the slack in the string, lacing, strap, or other flexible fastening, with a device through which the fastening passes, by reverse or rotative movement of this device, and means for retaining it in its reverse position. With the device made as seen at A, series of holes *m* are cut along each strap, through any one of which a tongue, *n*, projecting from the fixed piece *h* is slipped; these holes and the tongue enabling the length of that part of the strap tightened by the plate *d* to be adjusted as circumstances may render desirable. In the modifications seen at B C D and E, the same result is attained by placing the knots or stops in the lacing under the eyes *o* at a greater or less distance from the rotating or reversing device.

I claim a shoe-fastening device constructed to operate substantially as set forth.

GERARD SICKELS.
